WINDOW FRAME PUTTY GROOVE CLEANING
DEVICE

Marcus Tomarin, Chicago, Ill.

Application March 8, 1937, Serial No. 129,572

4 Claims. (Cl. 90—12)

This invention relates to a window frame putty groove cleaning device.

In the reglazing of windows, or openings in doors and the like, it is frequently a rather long and laborious task to remove the old, dried out putty, points, and the like, from the groove into which the glass is to be fitted. The device of my present invention is so arranged and constructed that this operation can be carried out in a simple and efficient manner in a much shorter time than was heretofore possible when the job was done by hand. My device includes a motor for driving a rotatable cleaning tool that extends into the putty groove and removes therefrom the old putty, points, and the like. Adjustable guide rollers are provided for bearing against surfaces at right angles to each other and on opposite sides of the groove, with means for holding the rollers in adjusted position in accordance with the depth of the groove so that the cleaning tool may clean the groove to the full depth thereof without, however, cutting into the wood. Thus, by the operation of my device, window frame putty grooves can be cleaned quickly and efficiently without danger of cutting into the sides of the groove or enlarging the same.

It is therefore an object of this invention to provide a window frame putty groove cleaning device of the general type indicated which is capable of efficiently and quickly removing the old putty without injury to the groove itself.

Other and further important objects of this invention will be apparent from the disclosures in the specification and the accompanying drawing.

This invention (in a preferred form) is illustrated in the drawing and hereinafter more fully described.

On the drawing:

Figure 1 is a side elevational view of a window frame putty groove cleaning device of my invention, showing the device in operation cleaning a groove in a window frame, the window frame and sill being shown in section.

Figure 2 is a bottom plan view of the device, partly in section and partly broken away.

Figure 3 is a fragmentary side elevational view of my device with a modified form of cleaning tool, with the upper portion of a window frame in cross section.

Figure 4 is an enlarged sectional view taken substantially along the line IV—IV of Fig. 1.

Figure 5 is a sectional view taken substantially

along the line V—V of Fig. 4 with parts in elevation.

As shown on the drawing:

The reference numeral 10 indicates generally a window frame putty groove cleaning device embodying the principles of my invention. Said device 10 comprises an electrical motor 11 having a lead-in wire 12 and plug 13 for connecting said motor to a source of electrical energy. The shaft 14 of said motor 11 carries a chuck 15, into which a cleaning tool 16 may be removably inserted and held. As shown in Fig. 1, the tool 16 is provided with a fluted or serrated cylindrical surface for rotation against one surface wall 17 of a groove 18 formed in the lower portion of 15 the window frame 19. The end surface of the cleaning tool 16 (Fig. 2) is provided with serrations or teeth 20 for cleaning out putty or the like from the other wall surface 21 of said groove 18.

In Fig. 3 there is shown a modified form of cleaning tool identified by the reference numeral 22 for cleaning a groove 23 in the upper rail 24 of a window frame.

It will be understood, of course, that the cleaning tool proper of my device may be of such shape and dimensions as to adapt it for the cleaning of any form or shape of groove used in the glazing of windows, doors, or the like. The cleaning surfaces of the tool, however, in all instances are so formed and designed as not to be capable of cutting into or injuring the wood forming the sides or walls of the groove to be cleaned. This is accomplished by giving a lead to the curved serrations 60 of the tool surface 35 such that the inner ends of said serrations 60 scrape first against the groove wall 17 near the bottom thereof, as shown in Fig. 1. The curved serrations or cutting edges 60 of the tool surface tend to lift up the glazing points by engagement 40 of a serration with a point, as the tool moves through a groove, to thus displace such glazing point. Rotation of the tool thus tends to lift out of the groove any points that may have been left therein, instead of driving them in, and to clean 45 the putty out of the groove instead of cutting into the wood.

The device 10 includes a support, indicated generally by the reference numeral 25, which is secured to the motor casing 11 and which comprises a pair of offset arms 26 and 27 spaced on opposite sides of the motor shaft 14 and joined by a plate 28, which extends transversely of said motor shaft 14 and is apertured, as at 29, to permit the shaft of the tool 16 or 23 to 50 55

extend therethrough and to permit also of the removal therethrough of the chuck 15 should that become necessary. A handle 30 is secured to said plate 28 and extends therefrom to facilitate movement of the device by hand along the groove that is to be cleaned.

A post 31 extends from the underside of the plate 28 in substantial alignment with the arm 27. Said post 31 is transversely bored near the 10 end thereof, as at 32, to receive a stem 33 carrying at its inner bifurcated end 34, a roller 35. Said stem 33 is movable in the bore 32 and may be held in adjusted position by means of a thumb bolt 36, the threaded portion 37 of which may 15 be screwed into said post 31 against a face of the stem 33. The bore 32 is counterbored, as at 39, and a coiled spring 40 positioned with one end bearing against the bottom of said counterbore and the other end bearing against the bifurcated 20 end 34 of the stem. With this arrangement, the spring 40 tends to urge the roller 35 and its supporting stem 33 into an inwardly projected position whenever released by the thumb screw 36, i. e., downwardly, as viewed in Figure 2. This 25 arrangement thus facilitates the adjustment of the roller 35 into rolling contact with a surface, such as the surface 41 (Fig. 1), in accordance with the depth of the groove 18.

A second roller 42 is carried by the plate 28 30 with its axis at right angles to the axis of the motor shaft 14 and with its roller portion extending through an opening 43 in said plate 28. Said roller 42 comprises a disk 44 (Figs. 4 and 5) having a flange 45 extending part way about its 35 periphery. Said disk 44 is provided with a threaded opening 46 for receiving the reduced threaded end 47 of a thumb screw 48. Said thumb screw 48 extends through a lug 49 which may be formed integrally with the plate 28. A smoothly tapered shoulder 50 is provided between the reduced threaded end 46 and the smooth shank 51 of said thumb screw 48. A coiled spring 52 is positioned about the shank 51 adjacent said shoulder 50, with an extended end 53 thereof bearing against a portion of the flange 45. Since the end 53 of the spring 52 is under torsional stress when the roller 42 is in the position shown in Fig. 4, there is a tendency, when the thumb screw 48 is loosened, for the spring to 40 move the roll 42 about its eccentric axis provided by the threaded end 47 to project the roller portion through the opening 43 against a surface, such as the surface 54 (Fig. 1). A ring 55 loosely mounted upon the flange 45 of said disk 44 is 45 thus brought into rolling engagement with said surface 54 and the thumb screw 48 is tightened up to hold the disk 44 in its adjusted position. Sufficient clearance, as at 56, is provided between the disk 44 and the plate 28 to keep the 50 ring 55 from binding during its rotation about the disk 44.

When it is desired to clean out a groove such as the groove 18 (Fig. 1), a small portion of the groove is first cleaned out by hand so that the 55 tool 16 can be properly fitted into that portion of the groove and the rollers 35 and 42 moved into their adjusted position and secured in place by the respective thumb screws 36 and 48. The motor 11 is then energized and the tool 16 gradually moved through the full length of the groove 18 from end to end. During such movement, the roller 35 rolls over the surface 41 and the roller 42 rolls over the surface 54 to limit the extent to which the tool 16 can extend in the 70 direction of either of the surfaces 17 and 21, re-

spectively. By so limiting the depth to which the tool 16 may move in the direction either of the walls of the groove, cutting of or injury to the walls themselves is thereby prevented.

The cleaning of a groove, such as the groove 5 23 (Fig. 3) with a modified form of tool 22 is carried out in a similar way, the rollers 42 and 35 bearing against surfaces at right angles to each other and on opposite sides of the groove. In this case the width of the cleaning face of 10 the tool 22 is the same as the width of the groove, so that the tool may be rotated in the groove up to the desired depth as determined by the setting of the rollers 35 and 42.

I am aware that many changes may be made 15 and numerous details of construction may be from the principles of this invention, and I, varied through a wide range without departing therefore, do not purpose limiting the patent granted hereon otherwise than necessitated by 20 the prior art.

The term "length of cut" is herein used to define the amount of cut performed by the cutter in horizontal direction as viewed in the drawing, and the term "depth of cut" is used to designate 25 the amount of cut in a vertical direction as viewed in the drawing.

I claim as my invention:

1. A window frame putty groove cleaning device comprising a motor, a groove cleaning tool 30 adapted to be removably secured to the shaft of said motor to be driven thereby, a support secured to said motor including a transverse plate through which said tool projects, a pair of rollers carried by said support on opposite sides of said 35 tool, means for adjusting said rollers in accordance with the depth and position of the window frame groove which said tool is to clean, and a handle secured to said support for moving said tool along the groove with the rollers in adjusted position traveling over surfaces of the window frame on opposite sides of said groove, one of said rollers being positioned below said plate with its axis parallel to the axis of said motor shaft and the other of said rollers being mounted above said plate with its axis at right angles 45 to the axis of said motor shaft and with a portion of its cylindrical surface extending through an opening in said plate against said window frame.

2. A window frame putty groove cleaning device, comprising a motor, a tool carried by the 50 shaft of said motor and having a fluted cylindrical face for rotation in a groove against a surface thereof, a support secured to said motor including an apertured plate extending transversely of the axis of said motor shaft with said tool projecting therebeneath, a roller mounted from said support with its axis at right angles to the axis of said motor shaft and with its roller portion extending through an opening in said 55 plate to bear against a surface of the window frame on one side of the groove, spring means urging said roller portion into lowered position through said opening, means for holding said roller in adjusted position, a second roller for bearing against another surface of said window frame mounted from said support below said plate with its axis parallel to the axis of said motor shaft, spring means urging said second roller toward the extended axis of said motor 70 shaft, and means for holding said second roller in adjusted position.

3. In a device of the class described, means for regulating the length of cut comprising a disc having a circular periphery, a ring rotatable on 75

the periphery of said disc as a roller, said disc being eccentrically mounted to adjust the ring toward or away from the adjacent side surface of a window frame, means for securing said disc in adjusted position, and means imposing torsional movement to said disc when said securing means is relieved to thereby automatically swing said disc and ring roller to bring the major axis of the disc into alignment with the cutter axis and reduce the axial distance between the cutter and the disc to a minimum.

4. In a device of the class described, means for regulating the length of cut comprising a disc adapted to swing in a plane parallel to the cutter axis for contacting the adjacent side surface of a window frame to control the length of cut, a 5 ring roller rotatably mounted on the periphery of said disc, and means for securing said disc in desired adjusted position.

MARCUS TOMARIN. 10
